KARL A. BRAUNING, OF STAMFORD, CONNECTICUT, ASSIGNEE TO THE YALE & TOWNE MANUFACTURING COMPANY, OF STAMFORD, CONNECTICUT

LOCK

Application filed August 24, 1929. Serial No. 388,101.

This invention relates to warded lock mechanism especially adapted for use in padlocks.

The object of this invention is to devise a warded mechanism which will allow for a number of key changes and which will give security against picking. A common weakness of warded mechanism resides in the fact that the key may be cut away to avoid all of the wards and thus directly operate the locking mechanism. My invention provides for means designed to prevent operation of a warded mechanism by any key other than that for which the wards and other mechanism were designed.

15 The invention is clearly disclosed in the following specification and in the drawing wherein Figure 1 is a longitudinal section of my padlock showing the various parts thereof. Figure 2 is a top and sectional view of 20 the lock operating cam and the warded and deadlocking mechanism for controlling the operation of the same. Figure 3 is a top and side view of my special key. Figure 4 is a side and top view of the movable ward. Figure 5 is a side and top view of a regular ward. Figure 6 is a view of the bottom assembly 25 plate. Figure 7 is a view of the deadlocking spring. Figure 8 is a side, front and bottom view of the casing for holding the wards in 30 position. Figure 9 is a top, side and bottom view of the lock operating cam.

Referring more particularly to the drawing, I have shown a casing 10 having mounted therein a shackle 11 which is controlled by 35 a rotary bolt 12. This rotary bolt 12 is operable by a cam 13 shown more specifically in Figure 9. This cam 13 has an upstanding portion 14 which is adapted to operate in a groove of the cam 12 to operate the same 40 against the pressure of the spring 15. All of this mechanism is described and claimed in an application of Charles Ledin, Serial Number 360,495 and forms no part of my invention.

45 The cam 13 rests at the top of the ward box 16 shown more particularly in Figure 8. Mounted below this cam in the box 16 are a series of wards 17, spacers 18 and a single camming ward 19, shown more particularly 50 in Figure 4.

The ward box 16 is equipped with a pair of lower lugs 20 which are adapted to fit in the slots 21 of the bottom assembly plate 22. This plate 22 holds the wards in position and is itself held within the lock casing by the 55 spun-over portion 23a of the padlock casing 10. This bottom plate 22 is also equipped with a pair of lugs 23 which are adapted to hold in position the deadlocking spring 24, as shown in Figure 2.

60 The various wards 17 and likewise the spacers 18 are equipped with cut-away portions 25, which cooperate with the indented portion 26 of the ward box 16 to hold the wards securely in fixed relation. The single 65 ward 19 is cut away at the point 27, so that it is movable with relation to the box 16 and the other wards. Similarly this ward 19 is equipped with a camming portion 28 which is adapted to operate the deadlocking spring 70 24 in a manner to be described presently.

75 This deadlocking spring, as may be noted from Figure 1, lies normally in a vertical position and has its end portion 29 normally resting in a groove 30 of the operating cam 13. It will thus be seen that while the deadlocking portion 29 is held within this groove 30, it will be impossible to rotate the cam by any tool inserted through the keyway and designed to avoid the wards. The movable 80 ward 19, on the other hand, when actuated by the proper key, will act through its camming portion 28 to cam the spring 24 into the position of Figure 2, so that 29 will be outside of the groove 30 and operation of 85 the cam 13 is possible.

86 The operating cam 13 is equipped with a bottom groove 31 into which the key 32 is adapted to enter for the purpose of directly 90 operating this cam in the usual manner. In order to prevent the entrance into this groove of a screw-driver or other tool surreptitiously used, a hump 33 is placed in this groove and the key is designed with a cut-away portion 95 34 to avoid this hump.

96 From the above specification, the operation of the padlock should be perfectly clear, but in order to more fully disclose the same, a brief summary of the operation will now be given.

The entrance of the key 32 into the operating groove 31 of the cam 13 is possible because the key 32 is cut away to avoid the hump 33. Rotation of the key 32 will be possible since this key is cut away to avoid the wards 17. The key is equipped, however, with one portion adapted to operate the movable ward 19 so that the camming section 28 of that ward, will operate the spring 29 and withdraw it from the groove 30 of the cam 13. Further rotation of the key will then operate the cam 13 to rotate the bolt 12 against the spring 15 and permit the ejection of the shackle.

While this invention has been described in its relation to a padlock, it should be understood that other uses of the same in all types of locks are possible, and applicant does not wish to be limited to the particular means described since modifications within the scope of the claims will be apparent to one skilled in the art.

I claim:

1. In a lock, a warded mechanism comprising a tubular casing, a series of wards mounted in said casing and secured against movement relatively thereto, a cam mounted for rotation in said casing, and having an upstanding and protruding lug portion, a spring member carried by said casing and adapted to deadlock said cam member, a movable ward in said series of wards, said ward being operable by the proper key to move said spring member out of deadlocking position, said tubular casing and its contents being insertable as a unit into the particular lock for which it is intended.

2. In a lock, a warded mechanism comprising a tubular casing, a series of wards mounted in said casing and secured against movement relatively thereto, a cam mounted for rotation in said casing and having a bolt actuating portion, a spring member secured at one end to said casing and adapted to deadlock said cam member, said spring member being in contact with said series of wards, a movable ward in said ward series, said movable ward being key operable to rotate said movable ward to move said spring out of cam deadlocking position.

Signed at Stamford, in the county of Fairfield and State of Connecticut, this twenty-third day of August, A. D. 1929.

KARL A. BRAUNING.
